UNITED STATES PATENT OFFICE.

NATHANIEL B. STONE, OF OUTLOOK, WASHINGTON.

LOCKING MECHANISM.

SPECIFICATION forming part of Letters Patent No. 758,941, dated May 3, 1904.

Application filed July 2, 1903. Serial No. 164,087. (No model.)

To all whom it may concern:

Be it known that I, NATHANIEL B. STONE, a citizen of the United States, residing at Outlook, in the county of Yakima and State of Washington, have invented a new and useful Locking Mechanism, of which the following is a specification.

The present invention relates to locking mechanism that may be employed for various purposes—as, for instance, securing the covers of money-boxes, toy safes, and the like—though not limited to use in connection with any particular kind or class of receivers or receptacles.

The object of the invention is to provide a novel and simple combination of elements which will securely lock two members against disassociation either through accident, inadvertence, or the attempts of an unauthorized person unacquainted with the method of operating the same, said combination, however, being easily operable by one having knowledge thereof.

Several embodiments are illustrated in the accompanying drawings, constituting a part of this application, and it will be understood that still other modified forms may be constructed without departing from the spirit or scope of the invention.

In the drawings, Figure 1 is a side elevation of a receptacle in which the improved locking mechanism is employed. Fig. 2 is a vertical sectional view through the upper portion of the same. Figs. 3, 4, and 5 are sectional views taken on the line $x-x$ of Fig. 2 and showing the manner of opening the cap. Fig. 6 is a vertical sectional view illustrating the cap removed. Fig. 7 is a detail perspective view of the upper portion of the receptacle. Fig. 8 is a vertical sectional view through a slightly-modified form of construction. Fig. 9 is a similar view through another embodiment of the invention. Fig. 10 is a horizontal sectional view taken on the line $y-y$ of Fig. 9.

Similar reference-numerals indicate corresponding parts in all the figures of the drawings.

Referring first to the embodiment illustrated

in Figs. 1 to 7, inclusive, it will be seen that 50 a receptacle-body 10 is employed which may be of any desired contour, being shown as cylindrical. This receptacle is provided with an upstanding contracted neck 11, having an annular groove 12 at its upper end, the upper 55 wall of the groove being formed by an outstanding flange 13. Detachably fitted over the neck and telescoped therewith is a cap 14, having a cylindrical body portion 15, which encloses said neck. This body portion is provided 60 with an exterior annular milled surface 16, by means of which the cap may be readily rotated. The body portion is provided in its inner face with an annular groove 17, which when the cap and neck are fitted together coats with the 65 groove 12 to form a raceway. In this raceway are placed a pair of freely-movable independent rollers in the form of balls 18 and 19, said balls being of sufficient diameter to engage in both grooves, as clearly illustrated in Fig. 2. 70 It will be observed that the groove 12 is considerably wider than the groove 17, and thus the cap may be moved longitudinally to a certain degree, though its detachment is prohibited by the balls engaging the flange 13. The 75 neck 11 is provided in diametrically opposite sides with seats 20 and 21, which open into the lower side of the groove 12. The cap 14 carries projections in the form of lugs 22 and 23, which extend across the groove 17 and 80 while located on opposite sides of the body portion are not diametrically opposite. In other words, when one of the lugs is located over a seat the other lug will be at one side of the opposite seat. In connection with this 85 structure there is preferably employed a retaining-sleeve 24, slidably fitted on the lower portion of the neck and movable over the groove 12, being held against removal by the outer edge of the flange 13, as illustrated in 90 Fig. 6, the diameter of the lower portion of the neck being less than the diameter of the upper portion, including the flange. The lower edge of the sleeve is provided with an outstanding rib 25, against which the lower 95 edge of the cap abuts when the latter is placed upon the neck. When the rollers 18 and 19 are in the seats 20 and 21, they are entirely

out of the groove 17 of the cap, and consequently are not interlocked with said cap. Furthermore, the lugs 22 and 23 will pass directly over the rollers without interference 5 from them; but when the rollers are loose in the raceway the cap and receptacle are thereby interlocked, while the sides of the lugs constitute shoulders which will move said rollers about in the raceway. To lock the cap 10 upon the receptacle, it is only necessary to place the rollers or balls in the seats and retain them by means of the sleeve 24, as illustrated in Fig. 6. The cap can then be placed upon the neck and upon being depressed will 15 move the retaining-sleeve downwardly, so that when the groove 17 comes into alignment with the balls it will drop into the raceway thus formed. The parts are thereby securely interlocked, and the rollers cannot again be 20 placed in their respective seats by merely rotating the members. Moreover, the natural method would be to draw the cap outwardly as far as possible before rotating it. This, it will be observed, would carry the path of 25 movement of the balls entirely away from the seats. In order to unlock and remove the cap, the following procedure is necessary, which is clearly indicated in Figs. 3, 4, and 5. The receptacle is held in substantially horizontal 30 position with one of the seats uppermost. The cap is then rotated, whereupon one of the balls, as 18, will drop into the uppermost seat 20, while the other will be moved against it by the projection 23, as illustrated 35 in Fig. 1. The movement of the cap is then reversed, thereby carrying the lug 23 rearwardly and permitting the ball 19 to gravitate in a similar direction. This movement is continued until the lug 22 is brought directly 40 above the ball 18, whereupon the lug 23 will be at one side of the lower seat 21, while the ball 19 will be located directly beneath said seat, all of which is illustrated in Fig. 4. The receptacle and cap are then rotated simultaneously in the direction shown by the arrows in 45 Fig. 5, which will carry the seat 21 and by means of the lug 23 the ball 19 upwardly until said ball drops into the seat. At the same time the lugs 22, being located directly in rear of the ball 18, will prevent the disengagement 50 of said ball. The balls now being in the seats, as already stated, are entirely out of the groove 12 of the cap and said cap may be readily removed. At the same time by grasping 55 the outstanding rib 25 of the retaining-sleeve said sleeve is moved outwardly simultaneously with the cap and the balls are held against displacement. It will be apparent that this structure is extremely simple, but at 60 the same time cannot be readily operated by a person unacquainted with the combination. In order that the operator may readily locate the lugs and seats, suitable scales, as illustrated in Fig. 1, are provided upon the body 65 portion of the cap and the adjacent faces of

the receptacle, these scales coacting in a manner readily understood. In order to make the combination less easily understood, the scale carried by the cap is preferably marked upon a collar 26, revolvably mounted upon the lower 70 portion of the body of the cap. Thus the scale may be rotated as desired, but may be brought into proper position by means of a suitable mark, as "27," located on the cap and coacting with any of the marks desired on 75 the scale.

In Fig. 8 there is illustrated a slightly-modified form of construction. In this instance the neck of the receptacle is provided in its inner face with an annular groove 17^a, while the cap 14^a has its body portion 15^a inserted within the neck and provided in its exterior face with an annular groove 12^a. In this instance the cap has the seats 20^a. In other words, the parts are exactly the reverse of 80 those illustrated in Figs. 1 to 7; but the operation is the same, as will be readily seen. It is therefore believed that no extended description of this structure will be necessary.

In Figs. 9 and 10 there is illustrated a very 90 simple form of the locking mechanism. The receptacle 10^b has an upstanding neck 11^b, provided with an annular groove 12^b. The neck is provided with seats 20^b, spaced apart, but located on the same side of said neck and opening into the groove. A cap 14^b is employed, which fits over the neck and has an internal annular groove 17^b coacting with the groove 12^b to form a raceway. In this instance the grooves are of the same width, and instead of balls cylindrical rollers 18^b and 19^b are employed. A single abutment 22^b is employed, which is carried by the cap and extends across the groove 17^b. A retaining-sleeve 24^b is provided, as in the former case, 95 while an index-collar 26^b is also employed. In this particular construction the receptacle is held in horizontal position with the seats uppermost, and the cap is then rotated until the lug 22^b will carry one of the rollers, as 18^b, 100 into one of the seats. The cap is then rotated in a reverse direction to permit the roller to gravitate to the lower portion of the raceway and is completely revolved to bring the projection 27^b on the opposite side of the same, 105 whereby upon a continued movement of the cap the roller 19^b will be elevated into the other seat, and the cap then being unlocked can be removed. It is intended in the specification and claims that the term "roller" 110 shall be broad enough to include balls, cylindrical rollers, as illustrated in Figs. 9 and 10, or comparatively thin disks.

From the foregoing it is thought that the construction, operation, and many advantages 115 of the herein-described invention will be apparent to those skilled in the art without further description, and it will be understood that various changes in the size, shape, proportion, and minor details of construction 120 125 130

may be resorted to without departing from the spirit or sacrificing any of the advantages of the invention.

Having thus described my invention, what I claim as new, and desire to secure by Letters Patent, is—

1. In mechanism of the class described, the combination with relatively revoluble members, of a movable device interlocked with the members, one of said members having a seat for the device, the other member having a portion arranged to engage the device to move it into coacting relation with the seat, said device when in the seat being out of co-
15 acting relation with one of the members.

2. In mechanism of the class described, the combination with relatively revoluble members, of a roller interlocked with both of the members, one of said members having a seat for the roller, the other member having a portion arranged to engage the roller to move it into coacting relation with the seat, said roller when in the seat being out of interlocking engagement with one of the members.
20

25 3. In mechanism of the class described, the combination with relatively revoluble and detachably-associated members, of a roller interlocked with the members and freely movable with respect thereto, one of said members having a seat for the roller, the other member having a shoulder arranged to engage the roller to move it into coacting relation with the seat, said roller when in the seat being disassociated from the other member.

35 4. In mechanism of the class described, the combination with revolubly-associated members having coacting grooves forming a raceway, of a roller movable in the raceway and engaging in both grooves, one of said members having a seat opening into its groove and constructed to receive the roller, and a shoulder located in the groove of the other member and constructed to abut against the roller, said roller when in the seat being out of the
40 groove of the other member.

5. In mechanism of the class described, the combination with revolubly and detachably associated members having telescoped portions, said portions being provided with annular co-
50 acting grooves in their adjacent faces forming a raceway, of a roller freely movable in the raceway, one of the members having a seat opening into its groove to receive the roller, and a lug extending across the groove
55 of the other member and constructed to abut against the roller when said roller is in the raceway.

6. In mechanism of the class described, the combination with revolubly-associated members, of rollers interlocking the members, one of said members having seats to receive the rollers, and means carried by the other member to move the rollers and retain certain of them in the seats.
60

65 7. In mechanism of the class described, the

combination with revolubly-associated members having coacting grooves forming a raceway, of independently-movable rollers located in the raceway, one of said members having spaced seats for the rollers opening into its groove, and means carried by the other member and located in its groove for moving the rollers into coacting relation with the seats, said rollers when in the seats being located out of the groove of the other member.
75

8. In mechanism of the class described, the combination with revolubly-associated members having coacting grooves forming a raceway, of rollers mounted in the raceway, one of said members having spaced seats opening into its groove and constructed to receive the rollers, and means carried by the other member and projecting into its groove for moving the rollers into coacting relation with the seats and retaining certain of said rollers therein.
80 85

9. In mechanism of the class described, the combination with revolubly-associated members having telescoped portions, said telescoped portions being provided with coacting grooves in their adjacent faces forming a raceway, of rollers freely and independently movable in the raceway, one of said members having seats opening into its groove and constructed to receive the rollers, and projections carried by the other member and located in its groove, said projections being constructed to engage the rollers and being movable over the seats when the rollers are in place therein.
90 95

10. In mechanism of the class described, the combination with a receptacle having an up-standing neck, of a cap having a flange telescoped within, and revolubly associated therewith, said neck and flange being respectively provided with coacting annular grooves forming a raceway, rollers freely movable in the raceway, seats formed in one of the telescoped portions and constructed to receive the rollers, and projections located in the groove of the other telescoped portion, said projections engaging the rollers when located in the raceway and being movable over said rollers when in the seats.
100 105 110

11. In mechanism of the class described, the combination with relatively revoluble and detachably-associated members, of a roller interposed between and interlocking with the members, one of said members having a seat to receive the roller and thus disassociate it from the other member, and a retaining device for holding the roller in the seat.
115 120

12. In mechanism of the class described, the combination with relatively revoluble and detachably-associated members, of a roller interposed between and interlocking with the members, one of said members having a seat to receive the roller and thus disassociate it from the other member, and means for retaining the roller in the seat after the members are detached.
125

13. In mechanism of the class described, the
130

- combination with relatively revoluble and detachably-associated members, of a roller interposed between and interlocking with the members, one of said members having a seat 5 to receive the roller and thus disassociate it from the other member, and a sleeve carried by the member and having a seat, said sleeve being movable over the roller when the members are disassociated.
14. In mechanism of the class described, the combination with relatively revoluble telescoped members having coacting grooves in their adjacent faces forming a raceway, of rollers freely movable in the raceway, one of 15 said members having seats to receive the rollers, and a sleeve slidably mounted on said member and movable over the seat when the members are disassociated.
15. In mechanism of the class described, the 20 combination with revoluble telescoped and detachably-associated members having coacting grooves in their adjacent faces, said grooves forming a raceway, of rollers revolubly mounted in the raceway, one of said members having seats to receive the rollers and thus disassociate them from the other member, means carried by said other member for moving the rollers into coacting relation with the seats, and a sleeve carried by the member having 25 30 the seats, said sleeve being movable over the rollers when they are located in the seats and after the disassociation of the members.
16. In mechanism of the class described, the combination with revolubly-associated and 35 relatively longitudinally movable members, of a movable device interposed between the members and interlocking therewith, one of said members having a seat to receive the device, means for moving the device into coacting relation with the seat, and exposed indicating 40 mechanism carried by the members for determining the positions of the seat and moving means.
17. In mechanism of the class described, the 45 combination with revolubly-associated and relatively longitudinally movable members, of a movable device interposed between the mem-
- bers and interlocking therewith, one of said members having a seat to receive the device, means for moving the device into coacting relation with the seat, and relatively movable coacting scales carried by the members. 50
18. In mechanism of the class described, the combination with revolubly-associated and relatively longitudinally movable members, of 55 a movable device interposed between the members and interlocking therewith, one of said members having a seat to receive the device, means for moving the device into coacting relation with the seat, and relatively movable 60 coacting scales carried by the members, one of said scales being movable upon the member carrying it.
19. In mechanism of the class described, the combination with revolubly-associated members 65 having an interposed raceway formed in both, of a roller movable in the raceway and interlocking with the members, one of said members having a seat to receive the roller, said roller when in the seat being disassociated 70 from the other member a projection carried by the other member and located in the raceway, and scales arranged on the exterior of the members for indicating the positions of the projection and seat. 75
20. In mechanism of the class described, the combination with revolubly-associated members having telescoped portions, said portions being provided with a raceway formed in their adjacent faces, a roller loosely fitted in the 80 raceway, one of said members having a seat to receive the roller, a projection carried by the other member and located in the raceway, a collar revolubly mounted on the exterior of the member having the projection, a scale located on the collar, and another scale mounted 85 on the other member and coacting therewith.
- In testimony that I claim the foregoing as my own I have hereto affixed my signature in the presence of two witnesses.

NATHANIEL B. STONE.
